(57) **CLAIM**

The ornamental design for a wheel well mounted safety guard, as shown and described.

DESCRIPTION

FIG. 1 is a perspective view of wheel well mounted safety guard according to my design shown for possible mounting on a school bus;

FIG. 2 is a front elevational view of the wheel well mounted safety guard of FIG. 1;

FIG. 3 is a left side view of the wheel well mounted safety guard of FIGS. 1 and 2; and,

FIG. 4 is a top view of the wheel well mounted safety guard according to the invention.

The broken lines in FIG. 1 showing an outline of a school bus and in FIGS. 1 and 3 showing a wheel well cover member are for illustrative purposes only and form no part of the claimed invention. In addition, no aspects of the invention are associated with the left, bottom or rear side views of the wheel well mounted safety guard.
